UNITED STATES PATENT OFFICE

2,287,478

FUEL PUMP FOR ENGINES

Edward A. Johnston, Chicago, and Raymond E. Peterson, Riverside, Ill., assignors to International Harvester Company, a corporation of New Jersey

Application April 20, 1940, Serial No. 330,750

20 Claims. (Cl. 123—140)

This invention relates to fuel injection pumps for internal combustion engines of the Diesel type.

One of the principal objects of the present invention is to provide a fuel pump for a multiple cylinder engine in which a single injection plunger is utilized for injecting the fuel to a plurality of cylinders.

Another object is to provide a simplified drive mechanism for a pump construction utilizing a single injection plunger and a plurality of timed delivery valves for delivering the charges of fuel in timed relation to independent cylinders.

Another object is to provide a simplified governor drive plunger to drive a valve timing mechanism in which the proper speeds are obtained for the different units with the use of a minimum number of parts and bearings.

Another object is to provide a pump construction in which the essential parts are formed as removable units which can be readily removed for service or replacement.

Another object is to provide a low pressure fuel supply pump as a separate unit cooperatively arranged with respect to the main pump drive mechanism so as to be driven thereby.

Another object is to provide a Diesel injection system with scavenging means continuously operable to withdraw leakage oil from the pump and the associated parts thereof and to return it to the supply tank without creating sub-atmospheric pressures in any of the parts from which the leakage oil is withdrawn.

The objects of the invention have been accomplished by the use of a unitary casing or housing in and on which all of the units of the injection system are mounted. In the particular 4-cylinder pump disclosed, a cam shaft mounted in the housing is driven at one-half crankshaft speed, said shaft carrying four cams for operating independent valves leading from a common pump discharge conduit to the independent cylinders of the engine. A governor and plunger driving shaft is mounted in the casing parallel to the cam shaft and driven therefrom by gears of such ratio as to operate the governor shaft at four times the speed of the cam shaft. This high speed rotation of twice the engine speed is very satisfactory for operating a centrifugal governor. The speed is also ample to give sufficient plunger strokes of the injection plunger to supply all of the cylinders with fuel charges by means of a single plunger. The injection plunger cylinder and housing, therefore, is formed as a special unit removable as such from the pump casing. The details of this unit are covered by the co-pending

application, Serial Number 330,749, filed April 20, 1940. Distributor valves are also mounted in a unit assembly which can be readily removed from the pump casing. The low pressure fuel supply pump and the scavenging pump are formed as a single unit readily removable from the casing.

The above brief description gives the general arrangement of the parts making up applicant's improved fuel injection system.

In the drawings:

Figure 1 is a diagrammatic view showing the exterior outlines of a pump unit embodying the invention and the fuel lines connecting the supply tank and the filter with the pump;

Figure 2 is a side elevation of the pump unit with the attaching housing at the end removed and with the side of the casing wall broken away in section to show the adjacent parts of the internal mechanism;

Figure 16 is a section taken on the line 16—16 of Figure 15;

Figure 17 is a section taken on the line 17—17 of Figure 15; and,

Figure 18 is a vertical section taken through

the center of the plunger unit transversely of the pump casing.

In the drawings, the main pump casing, or housing, 20 is formed as a casting, openings being cored, or bored, therein to provide for mounting and attaching the various units making up the injection system. A cover plate 21 is secured over an opening in the bottom of the casing. A cover 22 is secured over an opening at one side of the casing. An attaching member and drive gear covering housing 23 is secured to one end of the casing for rigidly connecting it to the crank case, or an extension thereof, of an engine. This type of construction is usually referred to as "flange mounting," all of the drive construction being enclosed. A transverse, vertical partition 24 divides the pump casing into two compartments. Said partition is of sufficient thickness to provide a vertical bore 25 in which the pump plunger unit, to be hereinafter described, is mounted. The bore 25 is uniform for a substantial distance, extending downwardly from the top face 26 of the casing 20. A second bore 27 of a substantially smaller diameter extends beyond the bottom of the bore 25 into the interior of the casing. An undercut channel, or recess, 28 is provided at the bottom of the bore 25 in the radial distance existing because of the difference in bore. Said channel forms an oil-collecting and transfer means, as will be herein-after described.

At one end of the casing 20 a drive shaft 29, which is adapted to be connected to drive mechanism from the engine by means of a driving element 30 rigidly keyed thereon, extends into the casing through a ball bearing assembly 31 diagrammatically shown, fitted in a bore 32 and held therein by suitable retaining means. Said shaft extends within the casing terminating in a ball bearing assembly 33 diagrammatically shown, mounted in a bore formed in the partition member 24. A plurality of cams 34 are formed on the shaft 29, each of said cams engaging the head portion of a tappet member 35 mounted for reciprocation in a bore 36 extending upwardly through the top wall 26 of the casing terminating in an enlarged bore 37. An oil-collecting channel 38 is formed in the annular space provided by the difference in diameters of the bores 36 and 37. Said channel has an upwardly directed edge which acts as a scraper to remove oil from the surface of the tappet member 35. A drainage channel 39 connects each of the channels 38 and extends at an angle downwardly, as shown in dotted lines in Figure 3 and in full lines in Figure 14. The leakage oil collected by said drainage means flows into the bore 25 collecting in the channel 28, previously described.

A gear 40 keyed on the shaft 29 drives a gear 41 mounted on a combined governor and plunger driving shaft 42 in a speed ratio of one to four. The shaft 42 extends through a ball bearing assembly 43 shown diagrammatically, mounted in a bore 44 formed in the end wall of the casing and retained therein by the mounting member 23. Said shaft also extends through the center partition 24 of the casing, being rotatably mounted therein by a ball bearing assembly 45, shown diagrammatically, mounted in a bore 46.

Beyond the partition 24 the shaft 42 is formed with an eccentric 47 on which a needle bearing assembly 48 is mounted, the needles contacting the eccentric 47 and the shell forming a drive

means for engaging a tappet cup 49 mounted for reciprocation in the bore 27.

Suitable means including a nut 50 are provided for retaining the needle bearing assembly in position on the eccentric 47. A reduced end portion 51 of the shaft 42 extending beyond the nut 50 is formed square in cross section, as best shown in Figure 5, to engage with driving relation a coupling member 52 pinned on a shaft 53. The shaft 53 drives the low pressure fuel supply pump and the scavenging pump, as will be described in detail.

The low pressure primary fuel supply pump for transferring fuel from the fuel tank to the injection plunger, and the scavenging pump are formed in a single casing 54. At the outer end a cover plate 55 closes two intersecting bores 56 and 57, as best shown in Figure 9, in which pump gears 58 and 59 are mounted in pumping engagement with each other. The gear 59 is keyed on the shaft 53. The gear 58 is free to rotate on a shaft 60. A fuel inlet compartment 61 is formed in the casing in communication with the bores 56 and 57. A conduit 62 communicating with the compartment 61 leads to the side wall of the casing where it is connected by a fitting to a supply conduit 63 leading to the bottom of a fuel supply tank 64, as shown in Figure 1. A fuel delivery compartment formed by a bore 61' communicates with the bores 56 and 57 to form an outlet. Said bore is connected by a conduit 63' with the top side of the casing where it is connected by a suitable fitting with a discharge line 65 leading to a filter 66, as shown in Figure 1.

It is necessary that a supply pump be provided which at all times pumps fuel in a quantity greater than is utilized by the injection plunger and at a uniform pressure. For that reason, as shown in Figure 12, a by-pass conduit 67 is connected to the conduit 64 and to a bore 68 communicating with the inlet compartment 61. A pressure relief valve 69 is mounted in the bore 68, being held in position by a compression spring 70. Said valve regulates the pressure in the discharge line from the supply pump, returning the excess fuel to the inlet side of the pump.

The scavenging pump is formed by intersecting bores 71 and 72 extending into the casing 54 from the end opposite the location of the supply pump. A gear 73 mounted on the shaft 53 is located in the bore 71. A mating gear 74 located in the bore 72 is mounted on the shaft 60. As shown in Figures 10 and 12, an inlet compartment 75 is provided in communication with the bores 71 and 72. A cover plate 76 extending over the face of the casing at the scavenging pump end thereof, closes the pump compartment, it being held in position by cap screws one of which is shown in Figure 3. A bore 77, shown in Figure 12, forms a communication between the drainage system of the pump casing, which will be further described in detail, and the inlet compartment 75 of the scavenging pump. An outlet compartment 78 communicating with the bores 71 and 72 is connected by a conduit 79 and a conduit 80 with a boss 81 to which a return fuel line 82 is connected by a suitable fitting, as shown in Figure 1. Said return line extends into the tank terminating above the highest liquid level therein whereby at no time will oil drain back through the return line into the pump.

The main drainage channel 39 leading from the distributor valves, and the channel 28, located at the bottom of the bore 25, have already been

described. A transverse bore 93 intersects the channel 28, as shown in Figures 3, 14, and 15. Said bore extends downwardly at an angle, as shown in Figure 15, the upper end being plugged and the lower end communicating with a vertical channel formed by a bore 95 shown in Figures 15, 16, and 17. The bottom end of the bore 95 is plugged. A transverse bore 96 intersects the bore 95 near its lower end and connects with a bore 97 shown in Figure 16. Said bore registers with the opening 77 in the cover plate 76, thereby delivering the drainage fuel to the inlet compartment 75 of the scavenging pump. A threaded bore 98 communicating with the conduits 96 and 97 provides by means of a suitable fitting, a connection for an air vent line 99 leading from the top of the fuel tank above the maximum fuel level therein for supplying air to the scavenging pump when there is not sufficient fuel to supply its positive displacement volume. This construction prevents the build-up of a substantial vacuum in the drainage system while permitting the pump to handle all of the leakage fluid drained by gravity into the channels provided for that purpose.

The injection plunger unit is fitted into the bore 25. The housing of said unit consists of a lower sleeve member 100 and an upper enclosure member 101. The sleeve member is provided with a shoulder at the top which centers the unit in the bore 25. A flange 102 at the top of the sleeve member seats on the surface 26 of the casing. The sleeve 100 is provided with a reduced lower end portion 103 which extends within the tappet cup 49. A generally cylindrical piston control member 104 is provided with an upper bearing shoulder 106 fitted in a bearing surface 107 formed at the upper end of the sleeve member 100. The lower end of the member 104 is of a smaller diameter to conform to the shape of the sleeve 100 and is provided with a bearing portion 108 fitted for rotation in a bearing surface provided at the lower end of the sleeve 100. Said sleeve is cut away intermediate its ends to provide for the engagement of a control rack 109 with gear teeth 110 formed around the intermediate portion of the control member 104.

An injection plunger 111 is mounted for rotation and reciprocation in a bore 112 formed in a cylinder member 113. Said member is provided with a head portion 114 fitted in an annular recess 115 formed in the flange of the sleeve member 100. The piston member is supported entirely from its flanged head portion, the remainder of the member being suspended out of contact with the control member 104.

The piston 111 is provided with a plurality of lugs 116 engageable with spline-like grooves 117 formed in the lower end of the piston control member 100. This construction provides for reciprocation of the plunger with respect to the control member and connects the members for rotation together whereby the angular position of the piston may be adjusted by movement of the control member 104.

The lower end of the plunger 111 is provided with a head 118 on which a spring retainer 119 is mounted. A compression spring 120 abuts the retainer 119 at its lower end and seats at its upper end against a shoulder formed at the bottom of the sleeve member 100. The spring 120 is located entirely within the tappet cup 49 and the head 118 of the plunger abuts the bottom of the cup thereby determining the piston position.

The upper end of the plunger 111 is formed

with an annular channel 121, a vertical channel 122, and a spiral cut-off channel 123 joining the vertical and the annular channels. This type of piston is well known in the prior art, being utilized to meter the fuel injected by the plunger dependent upon the position of the spiral cut-off portion with respect to inlet and by-pass openings in the wall of the cylinder.

Figure 3 shows the construction of the inlet and by-pass ports for the pump plunger. The head portion 102 of the piston member is formed with a pair of recesses 124 extending downwardly from the top surface of the member. Transverse bores 125 extending axially through the head portion intersect the recesses 124 and terminate in the cylinder bore. Screw plugs 126 are fitted to seal the outside ends of the bores, recesses 127 being formed in the head portion to accommodate the screw heads when the piston member is dropped into position. The particular construction of the injection unit including the delivery of fuel thereto and therefrom, and the piston control construction are covered by the co-pending application Serial Number 330,749, filed April 20, 1940, and are described here only in so far as is necessary to make a complete and adequate showing of the invention of this application.

A spacer member 128 seated on the top of the cylinder member 113 contains fuel supply conduits in the form of bores 129 and a substantially central bore 130 which provides a guide for a discharge valve 131. The head of said valve is seated on the top of the spacer member and is held against opening until the required pressure is obtained by a compression spring 131'. Said spring fits in an aligned bore 132 formed in a second spacer member 133 mounted on the spacer member 131. As best shown in Figure 18, discharge means from the plunger unit are provided by a screw threaded member 134 threaded into a bore formed in the spacer member 133 communicating with the vertical bore 132. The member 134 is formed with an internal channel 135 communicating with a channel in a connecting member 136 held in position against the spacer member 133 by the member 134 with the use of suitable sealing gaskets.

The cover or housing member 101, previously referred to, is provided with an internal bore of the same diameter as the external bore of the spacer blocks and the head portion of the piston 114. Said member also houses a filter 137 through which fuel passes from an inlet coupling 138 before passing downwardly to the supply ports of the cylinder. The member 101 is provided with a flange 139 by means of which the entire unit is secured to the casing 20 by means of studs 138' threaded into a bore 139' in the casing 20 as shown in Figure 14. A fuel supply conduit 140 leading from the filter 66 connects with the coupling 138 to supply filtered fuel to the final filter 137.

The connecting member 136 which is provided with the internal conduit 141, as shown in Figure 2, leads to the fuel distributor unit. Said unit consists essentially of a lower valve carrying block 142 and a distributor block 143. Said blocks are rigidly secured together with the abutting faces lapped to form a fuel-tight joint.

As shown in Figure 7, fuel under injection pressure from the injection plunger enters the valve block 142 through a threaded securing and conduit member 143. Passing through a transverse conduit 144, the fuel passes upwardly through a conduit 145 into a bore 146 formed in

the distributor block 143. A valve 147 is positioned with its guide stem in the bore 145 being seated on a seat formed around the upper end of said bore. A compression spring 148 located in the bore 146 maintains the valve in seated position until the desired pressure is reached.

From the bore 146 the fuel passes into a conduit 149 extending longitudinally of the distributor block 143. Said conduit communicates with a plurality of bores 150 extending upwardly into the distributor block. Each of said bores communicates with a vertical bore 151 extending vertically entirely through the valve block 142. A distributor valve 152 is mounted for reciprocation in each of the bores 151. The lower end of each valve is positioned to be engaged by one of the tappet members 35, previously described. The head portion 153 of each of the valves is provided with a seat adjacent the top of the bore 151 and is held against the valve block in seated position by a compression spring 153' located in the bore 150. It will be noted that the valve member is cut away adjacent the top to form an annular space therearound below the head portion 153. Fuel delivered to said space when the valve is opened is delivered through an angular conduit 154 to a vertical conduit 155 extending upwardly through the distributor block 143. Each of the conduits 155 is in communication with a fitting 156 threaded into the top of the distributor block.

To provide a dust-tight enclosure for the distributor unit, a housing 157 is mounted over the top of the casing 20. The fittings 156 and the inlet connection 138 of the fuel plunger unit project through openings in the top of said cover.

A conventional fly-ball governor is shown mounted on the shaft 42. The weights 158 are pivoted on a carrier 159 keyed on the shaft 42. The entire governor construction may be of any conventional type and has not been shown in detail. Force exerted by the fly-balls, or weights, 158, is exerted against a sleeve 160 rotatably and slidably mounted on the shaft 42. Said sleeve abuts a ball-bearing assembly 161 adapted to transmit the thrust of the governor to trunnion pins 162, as best shown in Figure 4, carried by a rockable control member 163. Said member is mounted on a shaft 164 carried by roller-bearing assemblies 165 and 165' suitably mounted in bores formed in the side walls of the casing 20.

The control member 163 is provided with an upwardly extending arm 166 at one side of the casing, as best shown in Figure 2, which is formed with a generally circular head portion 168 located between two thrust portions 167 of the control rack 109, previously described. Said control rack is mounted for reciprocation in the central partition 24 of the casing. At the end opposite the control member the control rack 109 is provided with an adjustable stop mechanism 168 adapted to abut a stop in the form of a boss 168' on the casing wall to limit the maximum amount of fuel which can be injected by the pump.

The control member 163 is also provided with an upwardly extending arm 169, shown in Figures 3, 4, and 5, to which a tension spring 170 is secured. Said spring is secured at the other end to a lever 171 rigidly secured to a shaft 172 extending transversely of the casing. Said shaft carries an adjusting arm 173 by means of which the tension on the spring 170 may be manually adjusted. To provide a maximum position, an adjustable stop mechanism 174 is located at one end of the casing 20 engageable with an exten-

sion of the lever 171 beyond the connecting point of the spring 170.

Although the operation of certain units of the fuel injection system of this invention have been explained in connection with the description of the component parts, a complete operation will now be described.

Fuel in the supply tank 64 is delivered through the conduit 63 to the inlet compartment 81 of the low pressure primary fuel supply pump. Said pump, being of a gear type, has a positive displacement depending on the speed of rotation of the driving shaft. The pump is built so that this displacement is sufficient to pump a larger supply of fuel than is used at any time by the injection system, the excess fuel being by-passed through the conduit 67 and the valve 69 back to the inlet of the pump. The spring 70 acts on the valve 69 as a pressure regulating means whereby the pump supplies fuel under a constant pressure to the conduit 65 leading to the oil filter 66. From said filter fuel passes through the conduit 140 through the filter 137, the bores in the spacer members 133 and 128, and into the recesses 124 formed in the flanged upper portion of the cylinder member 113.

From the crankshaft of the engine through suitable conventional gearing, not shown, power is transmitted to drive the primary shaft of the unit, which is the cam shaft 29, and through the gears 40 and 41 the secondary shaft of the unit, which is the governor drive and plunger operating shaft 42. With a four-cylinder pump, as illustrated, the cam shaft is driven at a speed one-quarter of the plunger operating shaft in order to provide an injection stroke for each of the distributor valves. In a two-cylinder pump it will be necessary to drive the plunger shaft at only twice the speed of the cam shaft. There is, however, a distinct advantage in driving the shaft on which the governor is mounted at a high speed, as greater power and better operating characteristics can be obtained from a centrifugal type of governor operating at high speeds.

The eccentric 47 of the plunger driving shaft 42, through the needle bearing assembly 48, drives the tappet cup 49 which in turn engages the bottom head portion 118 of the plunger 111. Said plunger is held against the cam by the spring 120 and is adjusted to vary the effective injection stroke by means of the control rack 109 operating in engagement with the gear 110 on the control member 163. As pointed out in the description, said control member is provided with axially spaced bearing portions which give accurate alignment of the member with a minimum of bearing surface, allowing the governor mechanism to act with a minimum of frictional resistance. The provision of a reduced end portion 103 on the sleeve member 100, which carries the injection plunger unit, allows the tappet cup 49 to extend upwardly over the lower end of the sleeve member. This construction reduces the overall height of the unit while permitting the use of a spring of suitable length and a tappet cup with sufficient bearing surface.

The injection plunger 111 is of a conventional construction known as the piston control port type. At the bottom of the stroke, fuel is drawn in through bores 125 intersecting the recesses 124 and the cylinder. As the plunger rises on the injection stroke, the top edge of the piston first passes over and cuts off communication with the supply ports. As the stroke continues, fuel

is delivered past the valve 131 into the conduit 141 leading to the distributor unit. When the curved wall of the piston passes over one of the inlet ports, fuel is by-passed down through the vertical slot 121 relieving the pump of pressure and stopping the delivery of fuel.

Fuel delivered to the distributor unit through the conduit 144, as shown in Figure 7, passes upwardly by the valve 147 into the longitudinal conduit 149 which supplies each of the bores 150 with fuel under pressure at each stroke of the injection plunger. The valve 147 acts to control pressure in the common conduit 149. Said valve does not open until the pressure has reached an amount determined by the spring 146 and closes as soon as the pressure drops on the injection plunger side of the valve.

The valves 153 in the bores 150 are opened in timed relation by the cams 34 on the shaft 29. Said cams, as will be noted by inspection of Figure 4, cover only a small angular portion of the relatively large portion of the shaft 29 which engage the tappets 35. It is necessary in an injection engine of this type to deliver the fuel at a high rate and at a high pressure to the injection valve, and to cut off the pressure and supply almost instantaneously at the termination of injection. For that reason, the valves 152 are opened very rapidly at the proper time and are also closed very rapidly. There is an important advantage in the distributor type mechanism of this type with utilization of a single plunger over the conventional injection system utilizing a separate injection plunger for each cylinder. It will be noted that the eccentric 41, which drives the injection plunger, is formed as a cylinder of a relatively large diameter. This construction provides for raising the pump plunger at a comparatively low rate of speed and for returning the plunger at the same rate. It is possible with a distributor valve unit to operate the plunger in this manner, as the valve which delivers the fuel to the injection nozzle may not be opened until the build-up of pressure in the system is sufficiently high to provide for proper injection regardless of the speed of the plunger and its distance of travel. The possibility of using a true eccentric for the pump plunger results in a piston travel which does not at any time exceed the piston travel on a multiple cylinder pump utilizing direct injection, although in the case of a four-cylinder engine the pump plunger travels four times the total distance of travel of any one plunger in a multiple plunger injection pump.

It will be understood that the drive shaft 29 for a pump unit constructed for a four-cylinder engine of the four-cycle type operates at half engine speed, giving two injections per revolution of the engine. The plunger driving shaft 42 operates at four times the speed of the shaft 29 or at two times the speed of the crank shaft of the engine, giving two injections per engine revolution.

The governor construction for controlling the quantity of fuel injected, as illustrated in the drawings, is of a conventional type, the basic principle being the control of the rack 109 by centrifugal governor weights 158 acting in opposition to the spring 170 on the control member 166. The mounting of one end of the spring on the manual adjustable lever 171 provides means for setting for different speeds of operation. The adjusting mechanism 168 at the end of the control rack, provides means for adjusting the maxi-

mum injection of fuel as determined by the angular position of the injection plunger 111.

Although injection pumps of this type are made of the finest materials available and the parts are precision fitted, there is always a certain amount of leakage past the fitted parts, increasing with wear. It has been customary to provide means for draining the leakage fuel outside the pump housing and allowing it to drip to the ground or be collected and discarded. In the pump of this invention provision has been made for collecting the leakage fuel and returning it to the fuel supply tank. The valves 152 fitted in the bores 151 necessarily withstand fuel at the injection pressures. There will therefore be some leakage past these valves into the recesses 38 at the bottom of the bores 37. The recesses are formed to provide knife-like edges which scrape the walls of the tappets 35 to remove fuel therefrom and prevent its passing downwardly through the bores 136 into the pump casing. Leakage fuel collected at the valves passes downwardly through the channel 39 into the bore 25 collecting in the channel 28 at the bottom thereof. Said channel is also shaped to remove fuel from the walls of the tappet cup 49. Inspection of Figure 18 will show that any fuel leaking past the plunger 111 will collect in the tappet cup 49 and overflow into the channel 28.

The leakage fuel collected from both possible leakage sources, as above pointed out, drains by gravity through the conduit 93 which, as best shown in Figure 15, intersects the channel 28 downwardly through the conduits 95, 96, 97, and 98 into the inlet chamber 75 of the scavenging pump, as shown in Figure 12. Said pump returns the leakage fuel to the fuel supply tank through the conduit 82, as shown in Figure 1. As the scavenging pump is of a capacity greater than the normal amount of leakage, an air line 99 is connected to the top of the fuel supply tank above the liquid level therein, and to the engine of the scavenging pump as shown in Figure 1 and Figures 16 and 17. This is an important element of the scavenging system as the creation of a partial vacuum in the collection conduits of the scavenging system would be very undesirable, acting to increase the fuel leakage and to draw lubricating oil past the tappets 35 and past the tappet cup 49 into the scavenging system. Another detrimental effect would be the drawing in of air through the seals and casing into the interior of the pump casing. Such air always contains dirt which is detrimental to the life of the wearing parts of the pump.

A general inspection of the fuel pump of this invention will show its extreme simplicity and accessibility for assembly and service. The casing 20 is such as to permit ready assembly of the drive shaft 29, which is inserted through one end thereof, and the driving shaft 42 which is inserted from the same end as a unit with the eccentric governor and the ball bearings assembly. It is wholly necessary to mount the control member 163 and the spring control structure, including the lever 171 and the shaft 172, through openings in the casing. The center partition 24 of the housing provides means for mounting the inner end of the shaft 25 and is also of sufficient thickness to provide the plunger bore.

The tappet cup 49 is inserted from the top of the casing and the injection plunger unit is entirely assembled as a unit before being mounted in the casing. Referring to Figure 18, the sleeve

member 100 and the housing member 101 enclose as a unit all of the parts of the injection plunger mechanism. This specific construction is covered by the copending application above referred to. However, the unit construction also forms a part of the present invention.

The distributor mechanism is formed as a unit including all of the parts of the assembly within the two blocks 142 and 143. These blocks may be removed as a unit for replacement or repair.

It will be seen that the fuel injection system as described is outstandingly simple and that it is composed of removable units which can be assembled rapidly and with accuracy and can be removed for replacement or repair. Although only certain preferred embodiments of the different units have been illustrated, it is to be understood that applicant claims as his invention all modifications falling within the scope of the appended claims.

What is claimed is:

1. In a fuel injection pump having a casing, a high pressure injection plunger mounted therein, a driving shaft and in combination therewith, a low pressure fuel supply pump mounted on the casing, means for supplying fuel to the inlet of said pump, means for conducting fuel under pressure from the pump to the injection plunger, a scavenging pump mounted on the casing, said casing being provided with a drain conduit for collecting leakage fuel in communication with the scavenging pump, conduit means in communication with a source of air at atmospheric pressure being also provided for drawing air into the scavenging pump to maintain substantially atmospheric pressure in the leakage fuel collecting conduit, and means for returning fuel from said scavenging pump to the fuel supply system.

2. In a fuel injection pump having a casing, a high pressure injection plunger mounted therein, a driving shaft and in combination therewith, a low pressure fuel supply pump mounted on said casing, means for supplying fuel to the inlet of said pump, means for conducting fuel under pressure from the pump to the injection plunger, a scavenging pump mounted on the casing at a low level thereon, said casing being provided with a drain conduit in communication with the scavenging pump for delivering leakage fuel thereto by gravity, conduit means in communication with a source of air at atmospheric pressure being also provided for drawing air into the scavenging pump to maintain substantially atmospheric pressure in the leakage fuel collecting means, and means for returning fuel from said scavenging pump to the fuel supply system.

3. In a fuel injection pump having a casing, driving means within the casing, a high pressure injection plunger mounted therein and driven by said means, a fuel supply pump mounted on said casing and driven by the driving means, means for supplying fuel to the inlet of said pump and means for conducting fuel under pressure from the pump to the injection plunger, a scavenging pump mounted on the casing and driven by the driving means, said casing being provided with a drain conduit in communication with the scavenging pump, conduit means in communication with a source of air at atmospheric pressure being also provided for drawing air into the scavenging pump to maintain substantially atmospheric pressure in the leakage fuel collecting means, and means for returning fuel from said scavenging pump to the fuel supply system.

4. A drainage system for fuel injection pumps having a plurality of movable elements working against fluid under high pressure comprising leakage collecting means adjacent each element through which it is possible for leakage to occur, drainage means connecting said collecting means, a positive displacement scavenging pump having an inlet, conduit means for delivering the collected fuel to said inlet, an outlet conduit from the scavenging pump, and an air vent line connected with the scavenging pump inlet whereby pressure in the drainage means is maintained at substantially atmospheric pressure.

5. A drainage system for fuel injection pumps having a plurality of movable elements working against fluid under high pressure comprising leakage collecting means adjacent each element through which it is possible for leakage to occur, drainage means connecting said collecting means,

20 a scavenging pump having an inlet, conduit means for delivering the collected fuel by gravity flow to said inlet, a fuel supply tank, an outlet conduit from the scavenging pump extending into the tank and terminating at a level above the maximum fuel level therein, and an air vent line connected with the scavenging pump inlet and with the tank terminating therein at a level above the maximum fuel level therein.

6. In a drainage system for fuel injection pumps having a casing with driving means and an injection plunger unit mounted therein, said casing serving as a lubricant reservoir, the combination of leakage collecting means adjacent each element through which it is possible for leakage to occur, said means being independent of the lubricant reservoir, drainage means connecting said collecting means, a scavenging pump having an inlet, conduit means for delivering the collected fuel to said inlet, an outlet conduit from the scavenging pump, and an air vent conduit connected with the scavenging pump inlet whereby pressure in the drainage system is maintained at substantially atmospheric pressure.

7. In a drainage system for fuel injection pumps having a casing with driving means and an injection plunger unit mounted therein, said casing serving as a lubricant reservoir, the combination of leakage collecting means adjacent each element through which it is possible for leakage to occur, said means being independent of the lubricant reservoir, drainage means connecting said collecting means, a scavenging pump having an inlet, conduit means for delivering the collected fuel by gravity flow to said inlet, a fuel supply tank, an outlet conduit from the scavenging pump extending into said tank and terminating at a level above the maximum fuel level therein, and an air vent conduit connected with the scavenging pump inlet and with the tank above the maximum fuel level therein.

8. In a fuel injection pump construction, a unitary casing having a horizontal top face, a vertical bore formed in the casing from said face, a removable injection plunger unit including inlet and outlet conduits fitted on the top of the casing and depending within said bore, a drive shaft rotatably mounted in the casing, a plurality of bores extending downwardly from the top face of the casing, tappet members mounted for reciprocation in said bores, said drive shaft being provided with cams engageable with said tappet members, a fuel distributor unit removably mounted on the top face of the casing over said tappet members, a driving shaft rotatably mounted in the casing parallel to the

drive shaft, gearing for driving said shaft from the drive shaft, and cam means carried by said shaft for operating the plunger unit.

9. In a fuel injection pump construction, a unitary casing having a single surfaced face, a vertical bore formed in the casing from said face, a removable injection plunger unit fitted on said face and depending within said bore, a drive shaft rotatably mounted in the casing, a plurality of bores extending downwardly from the face of the casing, tappet members mounted for reciprocation in said bores, said drive shaft being provided with cams engageable with said tappet members, a fuel distributor unit removably mounted on the face of the casing over said tappet members, a driving shaft rotatably mounted in the casing parallel to the drive shaft, gearing for driving said shaft from the drive shaft, and cam means carried by said shaft for operating the plunger unit.

10. In a fuel injection pump construction, a unitary casing having a horizontal top face, a vertical bore formed in the casing, a removable injection plunger unit fitted on the top face of the casing and depending within said bore, a drive shaft rotatably mounted in the casing, a plurality of bores extending downwardly from the top face of the casing, tappet members mounted for reciprocation in said bores, said drive shaft being provided with cams engageable with said tappet members, a fuel distributor unit removably mounted on the top face of the casing, said unit being formed with conduits for delivering fuel to a plurality of cylinders and a common supply conduit, valves carried by said distributor unit positioned to control the conduits therein, said valves being positioned to be engageable by the tappet members, a driving shaft rotatably mounted in the casing parallel to the drive shaft, gearing for driving said shaft at a speed which is a multiple of the speed of the drive shaft equivalent to the number of distributor valves, and cam means carried by said shaft for operating the plunger.

11. In a fuel injection pump construction, a unitary casing having a surfaced face, said casing being provided with a partition wall, a bore formed in the casing in the partition wall thereof, a removable injection plunger unit fitted on the face of the casing and depending within said bore, a tappet member mounted in said bore for driving the plunger unit, a drive shaft rotatably mounted in the casing, a plurality of bores extending from the face of the casing, tappet members mounted for reciprocation in said bores, said drive shaft being provided with cams engageable with said tappet members, a fuel distributor unit removably mounted on the face of the casing over said tappet members, a driving shaft rotatably mounted in the casing parallel to the drive shaft, gearing for driving said shaft from the drive shaft, and cam means carried by said shaft for operating the plunger driving tappet member.

12. In a fuel injection pump construction, a unitary casing having a horizontal face, said casing being provided with a vertical partition wall, a vertical bore formed in the casing in the partition wall thereof, a removable injection plunger unit fitted on the top of the casing and depending within said bore, a second bore formed in the partition in alignment with the first named bore, a tappet cup mounted in said bore for driving the plunger unit, a drive shaft rotatably mounted in the casing, a plurality of bores ex-

tending downwardly from the top surface of the casing, tappet members mounted for reciprocation in said bores, said drive shaft being provided with cams engageable with said tappet members, a fuel distributor unit removably mounted on the top surface of the casing over said tappet members, a driving shaft rotatably mounted in the casing parallel to the drive shaft, gearing for driving said shaft from the drive shaft, and cam means carried by said shaft for operating the plunger driving tappet member.

13. In a fuel injection pump construction, a unitary casing forming a lubricant reservoir having a horizontal top face, said casing being provided with a vertical partition wall, a vertical bore formed in the casing in the partition wall thereof, a removable injection plunger unit fitted on the top face of the casing and depending within said bore, a tappet member mounted in said bore for driving the plunger unit, a drive shaft rotatably mounted in the casing, a plurality of bores extending downwardly from the top face of the casing, tappet members mounted for reciprocation in said bores, said drive shaft being provided with cams engageable with said tappet members, a fuel distributor unit removably mounted on the top face of the casing over said tappet members, said unit being formed with conduits for delivering fuel to a plurality of cylinders and a common supply conduit, valves carried by said distributor unit positioned to control the conduits therein, said valves being positioned to be engageable by the tappet members, a driving shaft rotatably mounted in the casing parallel to the drive shaft and extending beyond the partition wall, gearing at one end of the casing for driving said shaft from the drive shaft, cam means carried by said shaft for operating the plunger driving tappet member, an auxiliary pump unit mounted on the casing at the end opposite the gearing, said unit including a supply pump and an independent scavenging pump, means for driving said pumps from the extending portion of the driving shaft, means for supplying fuel to the supply pump and therefrom to the injection plunger unit, and means independent of the lubricant reservoir for delivering leakage fuel from the distributor valves and the injection plunger unit to the scavenging pump.

14. In a fuel injection pump construction, a unitary casing having a horizontal top face, said casing being provided with a vertical partition wall, a vertical bore formed in the casing in the partition wall thereof, a removable injection plunger unit fitted on the top face of the casing and depending within said bore, a tappet member mounted in said bore for driving the plunger unit, a drive shaft rotatably mounted in the casing, a plurality of bores extending downwardly from the top face of the casing, tappet members mounted for reciprocation in said bores, said drive shaft being provided with cams engageable with said tappet members, a fuel distributor unit removably mounted on the top face of the casing over said tappet members, said unit being formed with conduits for delivering fuel to a plurality of cylinders and a common supply conduit, valves carried by said distributor unit positioned to control the conduits therein, said valves being positioned to be engageable by the tappet members, a driving shaft rotatably mounted in the casing parallel to the drive shaft and extending beyond the partition wall, gearing at one end of the casing for driving

said shaft from the drive shaft, cam means carried by said shaft for operating the plunger driving tappet member, an auxiliary pump unit mounted on the casing at the end opposite the gearing, and means for driving said unit from the extending portion of the driving shaft.

15. In a fuel injection pump construction, a unitary casing having a horizontal top face, said casing being provided with a vertical partition wall, a vertical bore formed in the casing in the partition wall thereof, a removable injection plunger unit fitted on the top of the casing and depending within said bore, a second bore of smaller diameter formed in the partition in alignment with the first named bore, the difference in diameter of said bores providing a leakage collecting channel, a tappet member mounted in said bore for driving the plunger unit, a drive shaft rotatably mounted in the casing, a plurality of bores extending downwardly from the top face of the casing, tappet members mounted for reciprocation in said bores, said drive shaft being provided with cams engageable with said tappet members, a fuel distributor unit removably mounted on the top face of the casing over said tappet members, said unit being formed with conduits for delivering fuel to a plurality of cylinders and a common supply conduit, valves carried by said distributor unit positioned to control the conduits therein, said valves being positioned to be engageable by the tappet members, a driving shaft rotatably mounted in the casing parallel to the drive shaft, gearing for driving said shaft from the drive shaft, cam means carried by said shaft for operating the plunger driving tappet member, a scavenging pump mounted on the casing, means for driving said pumps from the driving shaft, and means for delivering leakage fuel from the collecting channel to the scavenging pump.

16. In a fuel injection pump construction, a unitary casing provided with a vertical partition wall, a vertical bore formed in said wall, a removable injection plunger unit fitted on the top of the casing and depending within said bore, a second bore formed in the partition in alignment with the first named bore, a tappet cup mounted in said bore for driving the plunger unit, a drive shaft mounted in the casing, one end thereof being supported by one end of the casing, said partition wall being provided with a shallow bore coaxial with the drive shaft and providing a bearing for the inner end of said shaft, a plunger driving shaft mounted in the casing parallel to and below the drive shaft and rotatably supported by bearings in one end wall of the casing and in the partition wall, and gearing for driving said shaft from the drive shaft.

17. In a fuel injection pump construction, a unitary casing having a vertical wall formed with an attaching face, said casing being provided with a vertical partition wall, a vertical bore formed in the casing in the partition wall thereof, a removable injection plunger unit fitted on the top of the casing and depending within said bore, a second bore formed in the partition in alignment with the first named bore, a tappet cup mounted in said bore for driving the plunger unit, a drive shaft mounted in the casing being supported by a bearing at the attaching end of the casing and a bearing in the partition wall, a plurality of bores extending downwardly from the top surface of the casing, tappet members mounted for reciprocation in said bores, said drive shaft being provided with cams engage-

able with said tappet members, a removable fuel distributor unit removably mounted on the top surface of the casing, said unit being formed with conduits for delivering fuel to a plurality of cylinders and a common supply conduit, valves carried by said distributor unit positioned to control the conduits therein, said valves being positioned to be engageable by the tappet members, a driving shaft mounted in the casing parallel to the drive shaft and rotatably supported by bearings with one end wall of the casing and in the partition wall, gearing for driving said shaft from the drive shaft, said driving shaft extending beyond the partition wall, an auxiliary pump unit mounted on the casing at the end opposite the attaching surface, said unit including a supply pump and a scavenging pump, means for driving said pumps from the extension of the driving shaft, means for supplying fuel to the supply pump and therefrom to the injection plunger unit, and means for delivering leakage fuel from the distributor valves and the injection plunger unit to the scavenging pump.

18. In a fuel injection pump construction, a unitary casing provided with a partition wall providing support for bearings, a bore formed in the casing in the partition wall thereof, a removable injection plunger unit fitted on the casing and depending within said bore, a drive shaft mounted in the casing being supported by a bearing at one end of the casing and a bearing in the partition wall, a driving shaft mounted in the casing parallel to the drive shaft and rotatably supported by bearings at one end wall of the casing and in the partition wall, gearing for driving said shaft from the drive shaft, a centrifugal governor carried by the driving shaft, a plunger control member mounted for reciprocation in the partition wall, and control linkage operatively connected to the governor and the control member.

19. In a fuel injection pump construction, a unitary casing being provided with a partition wall providing support for bearings, a bore formed in the casing in the partition wall thereof, a removable injection plunger unit fitted on the casing and depending within said bore, a drive shaft mounted in the casing being supported by a bearing at one end of the casing and a bearing in the partition wall, a driving shaft mounted in the casing parallel to the drive shaft and rotatably supported by bearings at one end wall of the casing and in the partition wall, gearing for driving said shaft from the drive shaft, a centrifugal governor carried by the driving shaft, a plunger control member mounted for reciprocation in the partition wall, and a control member operatively connected to the governor and the control member, said member being pivoted on a transverse axis between the shafts.

20. In a fuel injection pump construction, a unitary casing having a horizontal top face, a vertical bore formed in the casing, a removable injection plunger unit fitted on the top of the casing and depending within said bore, a second bore of smaller diameter formed in the casing in alignment with the first mentioned bore, the difference in diameter in said bores providing a leakage-collecting channel, a tappet member mounted in said smaller bore for driving the plunger unit, a plurality of bores extending downwardly from the top face of the casing, tappet members mounted for reciprocation in said bores, means for operating said tap-

pet members, said casing being formed with leakage-collecting channels around the top of said tappet members, a leakage-collecting channel in communication with said channels and with the leakage-collecting channels in the plunger unit bore, a fuel distributor unit removably mounted on the top face of the casing over said tappet

members and including distribution valves and distribution conduits, a scavenging pump mounted on the casing, and means for delivering leakage fuel from the leakage-collecting channels to said scavenging pump.
